(57) **CLAIM**

The ornamental design for a surveying instrument, as shown and described.

DESCRIPTION

FIG. 1 is a front view of the surveying instrument showing our new design;

FIG. 2 is a rear view thereof;

FIG. 3 is a top plan view thereof;

FIG. 4 is a bottom view thereof;

FIG. 5 is a right side view thereof;

FIG. 6 is a left side view thereof;

FIG. 7 is a perspective view thereof;

FIG. 8 is a perspective view thereof;

FIG. 9 is an enlarged view of a display screen of the surveying instrument in FIG. 1;

FIG. 10 is a front view of another embodiment thereof;

FIG. 11 is a rear view thereof;

FIG. 12 is a top plan view thereof;

FIG. 13 is a bottom view thereof;

FIG. 14 is a right side view thereof;

FIG. 15 is a left side view thereof;

FIG. 16 is a perspective view thereof;

FIG. 17 is a perspective view thereof; and,

FIG. 18 is an enlarged view of a display screen of the surveying instrument in FIG. 10.

The broken line showing is for the purpose of illustrating environmental structure and forms no part of the claimed the design.
